SPLICING DEVICE

William M. Dice, Jr., Willoughby, Ohio, assignor, by mesne assignments, to The Ohio Rubber Company, Willoughby, Ohio, a corporation of Delaware

Application July 13, 1948, Serial No. 38,451

5 Claims. (Cl. 242—58)

1

This invention relates as indicated to a splicing device and more particularly to a device adapted to attach the leading end of a tape or web drawn from a new supply roll to a tape or web in course of being withdrawn from a nearly exhausted supply thereof.

There are many situations wherein it is desired continuously to withdraw a length of tape or the like from a supply thereof and to advance such tape to a machine which utilizes the same. One such machine is shown and described in application Serial No. 790,384, filed December 8, 1947 of George L. Meyers et al., "Method and Machine for Making Flexible Tubing," now Patent No. 2,539,853 dated January 30, 1951. In such machine a continuous length of rubber treated tape is wound about and adhered to a continuously advancing wire helix to form flexible tubing suitable for use as defroster hose and the like. Efficient operation of machines of this type requires that supply of material thereto must not be unnecessarily interrupted, and it is accordingly a primary object of my invention to provide a method and mechanism whereby when a supply of tape which is in course of being drawn upon is nearly exhausted the leading end of a new supply will be automatically spliced thereto without any interruption or even reduction in the speed of operation of the tubing forming machine or other machine utilizing such tape.

It is a further object of my invention to provide such mechanism which will require no supervision by an operator other than to periodically replace the exhausted rolls or spools.

Still another object is to provide such mechanism which will be of relatively simple construction requiring very little maintenance.

Other objects of the invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing—

Fig. 1 is a side elevational view of one embodiment of my new mechanism;

Fig. 2 is an end elevation view thereof;

Fig. 3 is a top plan view of such embodiment; and

Fig. 4 is a wiring diagram illustrating one form of control means for such mechanism.

2

Referring now more particularly to such drawing, the device there illustrated comprises a backing plate 1 on which the various component parts of the mechanism are mounted. Two spindles 2 and 3 are freely rotatably mounted on plate 1 and spaced therefrom by means of sleeves such as sleeve 4. Each of these spindles is identical and is adapted to have a roll of tape or similar web mounted thereon. A nearly exhausted roll 5 of such tape is shown on spindle 2 and a new full roll 6 is shown on spindle 3.

A rotary shear is also mounted on plate 1 intermediate and laterally of spindles 2 and 3. Such shear comprises a stationary horizontally disposed flat blade member 7 and a rockable member 8 provided with arcuate upper and lower blades 9 and 10 respectively. With member 8 in neutral position as shown in Fig. 1, there is a certain amount of clearance between each of blades 9 and 10 and intermediate fixed blade 7.

To facilitate assembly and maintenance, blades 9 and 10 may be integral with a short cylindrical portion 11 (Fig. 3) and member 8 may be in the general form of a split ring clamped about such cylindrical portion by means of screw 12. Opposed tension springs 13 and 14 are attached to such screw and adjustably secured to brackets 15 and 16 respectively. These springs serve to maintain the shears in horizontal or "neutral" position, as illustrated.

Adjacent such shears and to the left thereof as viewed in Fig. 1 is located the splicing mechanism proper. Such mechanism comprises two brackets 17 and 18 carrying a pair of vertically disposed rods 19 and 20 therebetween. Mounted on such rods for vertical reciprocation is an upper slide 21 and a lower slide 22. Each of such slides is secured to the piston of a respective pneumatic piston cylinder assembly 23 and 24. While each of such piston cylinder assemblies is provided with the usual internal spring for returning the piston when the air pressure is released, an auxiliary spring 25 may desirably additionally be employed connecting slide 21 and bracket 17 to assist in the return of such slide against gravity.

Upper slide 21 is provided with a pair of flat rollers 26 and 27 opposed to a corresponding pair of rollers 28 and 29 carried by lower slide 22. A laterally projecting lug 30 on slide 21 and a similar lug 31 on slide 22 is adapted to engage and rock member 8 when the corresponding slide is reciprocated.

As shown in Fig. 1, a length of tape 32 is in course of being drawn from supply roll 5 and, after passing under guide roller 33, such tape

passes between upper shear blade 9 and fixed blade 7, between the two opposed pairs of rollers carried by the respective slides and then about guide roller 34 and on to the tube building machine or other machine utilizing such tape. The length of tape 35 from reserve roll 6 is led over guide roller 36, between roller shear blade 10 and fixed blade 7, and the end of such tape adhered to the upper surface of roller 29. For the purposes of this description, it will be considered that the tape employed is a cotton fabric tape impregnated with a rubber composition which is quite adhesive in character. The mechanism of this invention is, however, adapted for use with many types of tapes and webs which may themselves be non-adhesive in character. In the latter case, the end of the tape may be lightly adhered to the upper surface of roller 29 by means of a small amount of adhesive, such adhesive being only sufficient to hold the end of the tape in place but permitting such tape to be immediately withdrawn from the roller by the exercise of a relatively light pull thereon. The upper surface of the end of such non-adhesive tape will have applied thereto a small amount of a stronger adhesive material.

A lever 37 pivotally mounted at 38 on plate 1 carries a roller 39 at its free end adapted to be held against the outer periphery of tape roll 5 through the action of weight 40 on the end of angle arm 41 rigidly secured to lever 37. A finger 42 on lever 37 to the other side of pivot 38 is positioned to engage and operate micro-switch 43 when lever 37 has been rocked sufficiently in a counterclockwise direction as viewed in Fig. 1. A similar lever 44 pivoted at 45 on plate 1 carries a roller 46 at its free end adapted to bear against the outer periphery of roll of tape 6. A weight 47 on the end of angle arm 48 serves to hold such roller in engagement with the tape roll. Finger 49 will engage and operate micro-switch 50 when roller 46 has moved sufficiently to the left as viewed in Fig. 1.

The operation of the above-described mechanism may now be understood as follows, reference being also had to the typical wiring diagram illustrated in Fig. 4 of the drawing. When substantially all of the tape has been withdrawn from roll 5, finger 42 operates micro-switch 43 which in turn, through a time delay relay 100, actuates a conventional solenoid operated three-way valve 101 to admit air pressure to the cylinder of piston cylinder assembly 23. Slide 21 thereupon descends and lug 30 engages member 8 to rock blade 9 to sever tape 32 in cooperation with fixed blade 7. Immediately after the severing of tape 32, rollers 26 and 27 engage corresponding rollers 28 and 29 with the tape of course therebetween. The trailing end portion of the severed tape which is still moving to the left as viewed in Fig. 1 is pressed against the leading end portion of tape 35 by the interaction of rollers 27 and 29. The two lengths of tape are thereby adhered together and the overlapping splice moves (to the left in Fig. 1) between pressure rollers 26 and 28 before the above-mentioned time delay relay causes the air pressure to be released from piston cylinder assembly 23 and rollers 26 and 27 to be again elevated. In normal operation the period of time during which the opposed rollers are held together may be only a fraction of a second. There is not the slightest interruption in the supply of the tape or web to the machine utilizing the same, the splice being made by the brief impact of roller 27.

The nearly exhausted roll of tape 5 will then be removed from spindle 2 and replaced by a new full roll. The end of this new supply of tape will be conducted under guide roller 33, between upper blade 9 and fixed blade 7 of the shears and then adhered lightly to the under surface of roller 27. As soon as slide 21 is moved upwardly again, springs 13 and 14 become operative to return the shears to neutral position. When roll of tape 6 now becomes exhausted, micro-switch 50 will be similarly actuated to energize time delay relay 102, thereby operating solenoid operated three-way valve 103 admitting fluid pressure to the other end of piston-cylinder assembly 24 to cause piston cylinder assembly 24 to move slide 22 upwardly. Lug 31 on such slide will engage member 8 to rock shear blade 10 in a clockwise direction to sever tape 35. Roller 29, continuing upwardly, forces the trailing end portion of such tape 35 against the leading end portion of the tape adhered to the under surface of roller 27, thereby splicing the two together. As above pointed out, such initial splicing is achieved by a momentary sharp impact rather than by merely squeezing the two tapes together. Instead of lightly adhering the end of the tape to the under surface of roller 27, if such tape is not very tacky, it may simply be allowed to rest on the upper surface of moving tape 35 beneath roller 27. Similarly, the end of a new supply of tape from roll 6 need not necessarily be adhered to roller 29 but may merely rest thereon. The sharp impact between the rollers serves to join the treated tapes even when they are not superficially sticky.

Other modes of applying the principle of the invention may be employed, change being made as regards the details described, provided the features stated in any of the following claims or the equivalent of such be employed.

I therefore particularly point out and distinctly claim as my invention:

1. Means for providing a continuous supply of adhesive tape comprising two spindles adapted to have tape supply rolls mounted thereon, a rotary shear comprising a fixed central blade and two arcuate blades respectively to either side of said fixed blade adapted to cooperate therewith when rocked about the axis of such arcs, two opposed pneumatic piston-cylinder assemblies adjacent said shears, a pair of rollers carried by the piston of each said assembly adapted forcibly to engage the other pair upon actuation of the corresponding piston-cylinder assembly, a lug on each said piston adapted to engage and rock said shears in a corresponding direction, resilient means adapted to return said shears to neutral position with each said arcuate blade spaced from said fixed blade, and control means for said piston-cylinder assemblies comprising rollers adapted to bear against the respective outer peripheries of such rolls of tape on said spindles, switches operative to control actuation of said respective piston-cylinder assemblies, and means responsive to movement of said last-named rollers toward said respective spindles adapted to actuate said corresponding switches.

2. Means operative to splice two adhesive webs together comprising two pneumatic piston-cylinder assemblies having their respective pistons axially opposed, a pair of rollers carried by each said pistons adapted to be brought into engagement with the opposed pair thereof, and a shears adjacent thereto adapted to sever a travelling web in timed relation to actuation of said piston-cylinder assemblies whereby the leading end por-

tion of a web placed between said opposed rollers may be adhered to the trailing end portion of a web travelling therebetween after severance by said shears.

3. A rotary shears selectively operative to sever one of two webs passing therethrough comprising a fixed intermediate blade, a rockable mount, two spaced arcuate blades carried by said mount and adapted to cooperate with said intermediate blade, resilient means normally operative to hold said mount with said two arcuate blades spaced respectively above and below said intermediate blade to permit the passage of two webs respectively therebetween, and means selectively operable to rock said mount to sever the desired web.

4. A rotary shears selectively operative to sever one of two webs passing therethrough comprising a fixed intermediate blade, a rockable mount, two spaced arcuate blades carried by said mount to either side of said intermediate blade and opposed thereto for respective shearing cooperation therewith when said mount is selectively rocked in opposite directions, whereby said two webs may respectively pass between a different one of said respective arcuate blades and said fixed blade, and means selectively operable to rock said mount to sever the desired web.

5. A rotary shears selectively operative to sever one of two webs passing therethrough comprising

ing a fixed intermediate blade, a rockable mount, two spaced blades carried by said mount to either side of said fixed blade respectively and adapted alternately to cooperate therewith in shearing relation when said mount is rocked in opposite directions, whereby such two webs may respectively pass between different rockable blades and said fixed blade, and means selectively operable to rock said mount in opposite directions.
